Attorney

UNITED STATES PATENT OFFICE.

JUAN ORTEGA GONZALEZ, OF MEXICO, MEXICO.

SPEED INDICATOR FOR VEHICLES.

Application filed February 22, 1922. Serial No. 540,065.

To all whom it may concern:

Be it known that I, JUAN ORTEGA GONZALEZ, citizen of the United Mexican States, residing at Mexico city, Federal District, Mexico, have invented certain new and useful Improvements in Speed Indicators for Vehicles, of which the following is a specification.

This invention relates to a speed indicator for automobiles.

The object of the invention is to provide a speed indicator which, when applied on the hub of a vehicle wheel, revolves so that an annular disk is slit by centrifugal force to exhibit different alternate fields in the cover of the speed indicator, when the speed of the vehicle exceeds that for which certain weights and a brake have been adjusted on the annular disk.

20 A high speed signal, which is not exposed when driving within towns, is provided for locking the disk against sliding, when running at high speed on roads where it is allowed.

25 Referring to the drawing: Fig. 1 is a front view of the speed indicator, a part of the cover being broken away and showing the disk in its non-operating position.

Fig. 2 is a similar view, but showing the 30 disk in a position exhibiting red fields.

Fig. 3 is a cross section of the indicator.

Fig. 4 is a plan view of the inside of the indicator box with the cover removed.

With reference to the drawing, (1) is a 35 sheet metal cover provided with a flange (2) and with cut-outs or transparent fields (3) covered with glass or similar material.

The indicator box or main part (6) has an inner wall (7) which rides on the hub 40 of the vehicle wheel, and also has an outer wall (8) engaged by the flange (2) of the cover.

Inside the box (6) are seen two parallel 45 grooves (9) located in the back plate of the box on equidistant chord lines from the center, in which projecting pins (10) of governor weights (11) engage.

The weights (11) have furthermore two 50 opposite slots (12) and are inserted from outside into corresponding grooves (13) made on the diametrical line of an annular disk (14), provided with alternate white and red fields (22) and (15). As seen, the 55 annular disk (14) is supported only by the sliding weights (11), and normally kept so that the red fields (15) will not coincide

or register with the transparent fields (3) of the cover (1), unless the vehicle wheel on which the indicator has been applied is being run at an excessive speed sufficient to 60 force the weights (11) by centrifugal force outward; due to the fact that the pins (10) of said weights are sliding in the grooves (9) and grooves (13). Thus the annular disk is obliged to turn a fraction of the periphery 65 sufficient to make the red fields appear through the transparent fields.

An adjustable brake (16) held by two screws (17) is used as an additional adjustment in order to maintain the annular disk 70 in a stationary position, until the centrifugal force of the weights (11) at a certain speed is sufficient to overcome the friction, so that the weights may force the annular disk to slightly turn, moving outwardly in 75 grooves (9) and (13).

In Fig. 1 a high speed signal locking device is illustrated and obstructs the outward movement of one of the weights. The device comprises a wing piece (18) connected 80 to a pivot (19) extending through the back plate of the box (6) and which at its opposite end inside the box has secured thereto a stop finger (20).

In Fig. 2 the high speed signal wing is 85 turned behind the indicator box, leaving the groove (9) unobstructed, in which case the annular disk is free to operate when the vehicle is driven at an unauthorized high speed. The positions shown in Figs. 1 and 90 4, when the wing is folded out, is only used when the vehicle is travelling in the open country.

As the car enters the city, the wing (18) is turned on its pivot and secured in any 95 suitable way to the position shown in Fig. 2, in order that the weights may be free to be acted on by centrifugal force, if the speed allowed were surpassed. Once the disk has been shifted to exhibit red fields, in order to 100 restore the annular disk to its non-operating position that is so that white fields are exhibited through the transparent fields (3).

The cover (1) is kept closed by seals (21) which must be broken in order to remove or 105 disturb the cover. If the seals (21) are found broken, as well as when the red fields appear in the transparent fields, and of course also if the high speed signal wing is being kept visible when vehicle is inside the 110 town limits, then the traffic authorities will impose the fine.

Having thus described my invention what I claim is:

1. A speed indicator for vehicles, comprising an annular casing having a front plate provided with transparent fields; a back plate having interior parallel channels on chord lines equidistant from the center of the casing, an annular disk having alternate coloured fields and provided with grooves on its diametrical lines, and a sliding weight in one of the grooves having a projection sliding in one of the channels.
2. A speed indicator for vehicles, comprising an annular casing having a back plate fitting on a wheel hub, and having transparent fields in the cover of said casing, said back plate having interior parallel channels on chord lines, equidistant from center of said casing, an annular disk having alternate coloured fields and grooves, a sliding weight in each groove with a projection sliding in each channel, a signal wing obstructing when exposed one of said channels and locking said disk, and an adjustable brake for said disk.
3. A speed indicator, comprising a casing adapted to be rotated having a back plate and a cover, said cover having transparent fields, and said plate being provided with grooves; a disc in said casing having grooves and provided with fields of different colors; and means associated with both sets of grooves for rotating said disc with respect to said casing when said casing is rotated,

thereby to bring different color fields opposite the transparent fields.

4. A speed indicator, comprising a casing embodying a back plate provided with grooves and also embodying a cover provided with transparent fields; a disc in said casing having grooves therein and provided with fields of different colors; adjustable means in said casing to frictionally engage said disc; and means associated with both sets of grooves for rotating said disc with respect to said casing in order to change the color under said transparent fields.

5. A speed indicator comprising a casing embodying a back plate provided with grooves and also embodying a cover provided with transparent fields; a disc in said casing having grooves therein and provided with fields of different colors; adjustable means in said casing to frictionally engage said disc; weights associated with both sets of grooves for rotating said disc with respect to said casing in order to change the color of the disc which is visible under said transparent field; and means for maintaining the indicator in an inoperative condition.

6. A speed indicator as claimed in claim 5, in which the means for maintaining the indicator inoperative coacts with the disk to thereby prevent its rotation.

In testimony whereof I have affixed my signature.

JUAN ORTEGA GONZALEZ.
